Primary Examiner — Rhea Shields(74) *Attorney, Agent, or Firm* — Dentons US LLP(57) **CLAIM**

We claim the ornamental design for a barrel of an intraruminal device, as shown and described.

DESCRIPTION

FIG. 1 is a perspective view of a barrel of an intraruminal device, showing our new design;

FIG. 2 is a front view, the back view being a mirror image thereof;

FIG. 3 is a side view, the other side view being a mirror image thereof;

FIG. 4 is a top plan view thereof;

FIG. 5 is a cross sectional view, taken along line 5-5 in FIG. 2; and,

FIG. 6 is an enlarged view, taken from FIG. 5.

In the drawings, the broken lines are for the purpose of illustrating portions of the barrel of an intraruminal device that forms no part of the claimed design.
